UNITED STATES PATENT OFFICE.

JOSEPH G. BARKER, OF WATERTOWN, ASSIGNOR TO MARCH BROTHERS,
PIERCE & CO., OF BOSTON, MASSACHUSETTS.

SHIRT.

SPECIFICATION forming part of Letters Patent No. 253,256, dated February 7, 1882.

Application filed December 12, 1881. (No model.)

To all whom it may concern:

Be it known that I, JOSEPH G. BARKER, of Watertown, in the county of Middlesex and State of Massachusetts, have invented a new and useful Improvement in Shirts, of which the following, taken in connection with the accompanying drawings, is a specification.

My invention is designed more especially for application to woolen shirts—such as are worn by bicyclers and other sportsmen—and is an improvement upon the shirt now in very general use among such men, and which is made to open in the center of its front, and is provided upon each side of said opening with a series of eyelet-holes, through which a lacing-cord of bright-colored silk is run and tied in a bow-knot at the throat, said shirt also being provided with a pair of flaps upon the inner side of said front, extending from the lower end of the opening to a point some distance below the collar of the shirt, which flaps are buttoned together before the shirt is laced up. This makes a very pretty shirt-front, and it is in great demand among the class of men who wear woolen shirts; but there is a serious objection to its use in the fact that a great deal of time is wasted in putting on and taking off the shirt, due to the fact that the lacing-cord has to be withdrawn from the eyelets for the greater part of the length of the opening in the front before the shirt can be taken off, and after the shirt is put on again the lacing-cord has to be passed through all of the eyelets from which it had previously been removed.

To obviate this objection and produce a shirt having all the good features of the old shirt, and that can be put on or taken off as readily as an ordinary shirt, is the object of my present invention; and it consists, first, in a shirt provided with a double front, arranged to be buttoned at one side of the center of said front, and with a lacing-cord run through two series of eyelets, one upon each side of the central vertical line of said front, whereby the shirt has the appearance of having its front opening laced up, while at the same time the shirt may be put on or taken off without materially disturbing the lacing-cord.

It further consists in the application to a shirt of ordinary construction of a supple-

mentary front, secured to said shirt at one side and along its bottom by sewing or stitching and along its other vertical side by means of buttons and button-holes or other suitable separable fastenings, said front being provided with two narrow plaits or folds extending from top to bottom thereof, the free or movable edges of which are parallel with and in close proximity to each other, and on a line with the center of the shirt-front, in combination with a series of eyelet-holes formed in each of said plaits at equal distances from each other and from the edge of said plait, and a lacing-cord passed alternately through an eyelet-hole in one plait and then through an eyelet-hole in the other plait or fold, so as to lace said plaits together, as will be described.

It further consists in the combination, in a shirt, of a supplementary front permanently secured to the shirt-body along one of its vertical edges and along its bottom edge by sewing or otherwise, and detachably secured to said body along its other vertical edge by buttons and button-holes or other separable fastenings, a series of eyelet-holes upon each side of and parallel with the vertical center line of said front, an eyelet formed in each end of the collar or collar-band, and a lacing-cord run through the eyelet-holes in said front, alternately from one series to the other, from the bottom to the top, and having one of its ends passed through one of the eyelet-holes in the collar and the other end through the eyelet-hole in the other end of the collar or collar-band, and then tied in a bow-knot, as will be further described.

Figure 1 of the drawings is an elevation of a woolen shirt now in general use with the front laced up, and Fig. 2 is an elevation of the same shirt with the front opening partly unlaced and the upper portion of the front turned back to expose the buttons beneath the lacing. Fig. 3 is an elevation of a shirt-front embodying my invention. Fig. 4 is an elevation of the same shirt with the front unbuttoned and its upper portion turned back; and Fig. 5 is a transverse section through the shirt-front, and showing a portion of same in elevation.

In Figs. 1 and 2 is represented the shirt now in common use by sportsmen and bicyclers, in

which A is the body of the shirt, having an opening or slit, *a*, in the center of its front, upon either side of which is a row of eyelet-holes, *b*, through which is passed the lacing-cord *c*, as shown in Fig. 1.

B is the collar, secured to the body in the usual manner, and having in each end thereof, near its junction with the body, an eyelet-hole, *d*, through which the lacing-cord *c* is passed 10 and then tied in a bow-knot, as shown in Fig. 1.

To the inside of the body A and upon each side of the slit *a* is secured a flap, C, so arranged that one of said flaps shall overlap the other, so that they may be secured together 15 by the buttons *e e* and suitable button-holes.

In Figs. 3 and 4 the body A and collar B are cut and secured together in the same manner as the same parts in Figs. 1 and 2; but instead of applying the flaps C C (shown in 20 Fig. 2) to the inside of the body and lacing together the two sides of the slit *a*, formed in the front thereof, as shown in Figs. 1 and 2, a supplementary front, D, is permanently secured to the body A of the shirt, along the 25 vertical edge *f*, the bottom edge, *g*, and a small part of the lower portion of the vertical edge *h*, by one or more rows or lines of stitching, *i*. The remaining portion of the edge *h* of said front is supplied with a "fly," *j*, in which are 30 formed button-holes *k k*, by means of which and the buttons *l l l* and button-hole *m*, which is made through the front D, said edge *h* of the front D is secured to the body of the shirt, the body of the shirt upon opposite sides of the 35 slit *a* meeting, or nearly meeting, behind the front D, as shown in Figs. 4 and 5.

The front D is provided with two folds or plaits, *n* and *n'*, extending from the top of said front to a point near its bottom, the free or 40 movable edges of which are toward and parallel with each other, as shown in Fig. 3. In each of these folds are formed a row or series of eyelet-holes, *o o*, through which the colored silk cord *p* is laced from the bottom upward, 45 one end of the cord *p* being finally passed through an eyelet-hole, *q*, formed in one end of the collar or its band, and the other end of said cord being passed in like manner through a similar eyelet-hole, *q'*, formed in the other 50 end of the collar or collar-band, and the two ends of the cord being tied in a bow-knot, as shown in Fig. 3.

The dotted lines *r r* represent lines of ornamental stitching in bright-colored silk corresponding in color with the cord *p*. 55

It will be seen that to remove the shirt when upon the person it is only necessary to untie the lacing-cord, remove the same from the single eyelet-hole *q*, and unbutton the buttons *l l* *l*, as shown in Fig. 4, and when the shirt is 60 placed upon the person it is only necessary to button the three buttons *l*, pass the cord *p* through the eyelet-hole *q*, and tie the cord to complete the toilet, so far, at least, as the shirt is concerned, which is considered a very important advantage over the shirt represented in Figs. 1 and 2, which requires the removal of the cord from nearly all of the eyelet-holes to permit the removal of the shirt and the insertion of the cord endwise through nearly all 65 of the eyelets every time the shirt is put on.

What I claim as new, and desire to secure by Letters Patent of the United States, is—

1. A shirt provided with a double or supplementary front, having a lacing-cord run 75 through two rows or series of eyelet holes arranged upon each side of the central vertical line of said front, and detachably secured to the body of the shirt along one of its vertical edges by buttons and button-holes or other separable fastenings, substantially as described.

2. In combination with a shirt of ordinary plain construction, a supplementary front permanently secured along its bottom and one vertical edge to the body of the shirt and detachably secured along its other vertical edge by buttons and button-holes or other separable fastenings to said body, a pair of folds or plaits in the center of said front and extending from its top to a point near its bottom, a series of 85 eyelet-holes in each of said plaits, and a lacing-cord run through said eyelet-holes, substantially as and for the purposes described.

3. In combination with a shirt of ordinary plain construction, the supplementary front D, 95 provided with the folds or plaits *n* and *n'*, and secured along one of its vertical edges to the body of the shirt by buttons and button-holes or other separable fastenings, the two series of eyelet-holes *o o*, formed in the folds *n* and 100 *n'*, the two eyelet-holes *q* and *q'*, formed in the opposite ends of the collar or collar-band, and the lacing-cord *p*, all arranged and adapted to operate substantially as described.

Executed at Boston, Massachusetts, this 10th 105 day of December, A. D. 1881.

JOSEPH G. BARKER.
